United States Patent Office

Des. 232,631
Patented Sept. 3, 1974

232,631

WHEEL CENTER

John Siroonian, 2640 W. Bullard St., Fresno, Calif.
93705, and Delmer D. Scott, Los Angeles, Calif. (5020
Gloria Ave., Encino, Calif. 91316)

Filed June 11, 1973, Ser. No. 368,638

Term of patent 14 years

Int. Cl. D12—16
U.S. Cl. D12—205

Fig. 1.

Fig. 2.

FIG. 1 is a front elevational view of a wheel center showing our new design,

FIG. 2 is a cross-sectional view taken on the line 2—2 of FIG. 1;

FIG. 3 is a rear elevational view; and

FIG. 4 is a side elevational view thereof.

The broken line showing of the wheel rim in FIGS. 1, 3 and 4 is for illustrative purposes only.

We claim:

The ornamental design for a wheel center, as shown and described.
